Richard J. Jacken

UNITED STATES PATENT OFFICE.

WARREN M. OSBORN, OF CHICAGO, ILLINOIS.

RAIL ANCHOR.

Application filed December 10, 1925. Serial No. 74,503.

My invention relates to anchors for railroad rails, and its object is to provide a new and improved rail anti-creeper which when attached to the rail abuts against the sides 5 of adjacent ties and acts as a two-way anti-creeper by transmitting to the ties the longitudinal movements or thrusts of the rail in both directions caused by the expansion and contraction of the rail or by its wave movement under traffic.

In the accompanying drawings, Fig. 1 is a top plan view of a rail-anchor constructed in accordance with my invention and applied to a rail between two ties; Fig. 2 is a side view 15 partly in elevation and partly in cross-section and with the wedge or key of Fig. 1 omitted; Fig. 3 is a sectional view taken on the line 3—3 in Fig. 2 looking in the direction of the arrows; Fig. 4 is a detail view 20 showing a variation in the form of the foot of the anchor leg abutting against the ties, and Fig. 5 is a perspective view of a suitable key or wedge which may be employed.

In the drawings the reference letter A 25 designates the flanged base of a rail, B its web broken away to omit its head for simplicity of illustration, and C a pair of the cross-ties between which the anchor is located when mounted on the rail.

My improved rail anchor is formed in one-piece from metal having considerable resiliency, such for example as spring steel or cast malleable iron, and consists of a member such as a cross-plate or bar 1 which underlies the rail between adjacent ties and 35 grips its base, and a pair of angular legs 2 extending laterally and downwardly from one end of the cross-member and adapted to lie between and abut against the corresponding sides of the adjacent ties, the legs being 40 preferably provided at their outer ends with downturned feet 3 to provide more extended bearing surfaces against the ties. At its end opposite to the legs the cross-plate 1 is 45 provided with a reversely bent jaw 4 which grips one flange of the rail base when the anchor is in position thereon, and at its leg end the cross-plate is provided with an upwardly extending shoulder 5 which has a 50 vertical face 6 at its lower inner portion to engage the edge of the opposite flange of the rail base, the inner upper end of the

shoulder 5 being beveled outwardly as at 7 to facilitate the assemblage of the anchor on the rail base.

The cross-plate 1 preferably is slit longitudinally at its center so that its shoulder end is divided or sectional; when the plate is formed of spring steel the slit may extend into the jaw 4 leaving a narrow bridge 8 at 60 the inner end thereof, and when the plate is of other resilient metal, such as cast malleable iron, the slit will preferably extend only to about the base of the jaw 4.

The dimensions of the parts of the plate 65 are such that when it is assembled upon a rail-base one edge of the latter fits under the jaw 4 and the other edge abuts against the shoulder 5 as shown in Fig. 3; in assembling the plate on the rail the jaw 4 is hooked onto 70 one flange of the rail-base and crowded or driven into gripping position thereon, and the resiliency of the jaw causes the shoulder 5 during this operation to hug the lower face 75 of the rail base and to move upwardly to snap into position against the opposite flange thereof when the jaw is brought to its final position so that the corresponding flange of the base seats against the shoulder, the beveled face 7 of the shoulder facilitating 80 the passage of the rail base to place and crowding its opposite edge under the jaw. When the plate is assembled on the rail the resiliency of its jaw 4 holds the shoulder 5 under compression against the rail flange 85 with a strong grip, and the engagement of the feet 3 of the legs 2 with the opposite ties tends to hold this end of the plate up against the rail base so that the grip of the shoulder 5 on the rail is maintained.

The leg end of the plate is preferably provided with an inclined seat 9 extending through the shoulder on a line with the inclined upper surface of the rail-flange, and a key 10 is adapted to fit the seat and overlie 95 the rail-flange to hold this end of the plate in its assembled position on the rail-base so that it will not be accidentally displaced or released. A key is preferably, but not necessarily, employed, and is of such shape that it may be easily pushed into its seat after the anchor is assembled on the rail, it being obvious that the key will draw this end of the cross-plate snugly up against the rail-

base and will aid in holding it in that position. The key is preferably wedge shaped in both thickness and width, and is preferably provided with an enlarged arrow shaped or beveled leading end as at 11 to facilitate its spreading the sections of the shoulder sufficiently and with an enlarged head as at 12, so that when it is in its seat the shoulder sections 5 will fit in place between these enlargements to lock the key against accidental withdrawal or displacement in either direction. The key may be of such width that when seated it may or may not spread the sections of the shoulder beyond their normal separation; when the jaw 4 has a strong grip on the rail base its spring action will ordinarily be sufficient to hold the faces 6 of the shoulder 5 in gripping engagement with the rail, but in case the rail is of such section that its flange does not open the jaw 4 sufficiently to produce enough spring action or resiliency to attain this result at the opposite end of the plate a key may be used having sufficient width to spread the shoulder sections 5 beyond their normal separation so that the outer ends of the face 6 will grip or bite into the rail-flange.

The length or span of the legs 2 varies to conform to the general practice of spacing the ties on the railroad to be equipped; for example, on bridges the usual practice is to space the ties twelve (12) inches between centers, and in ballast track they are differently spaced according to the number of ties specified for a given length of rail, and the span of the legs may be determined accordingly. The ends of the legs are turned down to form feet 3 to provide extended bearing surfaces against the ties, and in some cases the feet may be widened as shown in Fig. 4. The point of contact of the legs with the ties is below the base of the rail, so when a rail tends to creep the resistance of the corresponding tie produces an upward thrust on the associated leg and aids the rail-engaging devices on the plate to tighten the grip on the rail. In creeping of the rail in either direction the tie resistance is transmitted to the plate, and the grip of the anchor at the leg end is extended to include both sections of the shoulder 5 when the plate is slit and the key is employed as the latter transmits the stress on one section to the other so that two points or bearings of resistance are provided.

As the anchor grips or clamps the rail and bears against adjacent ties it resists all tendency of the rail to creep in either direction; and as the tie-engaging legs of the anchor are near its end the stress or thrust due to the resistance of the ties in either direction tends to skew the anchor on the rail and draw the jaw up onto one flange of its base and wedge the appropriate end of the

face of the shoulder against the edge of its associated flange to increase the grip or hold of the anchor on the rail.

I claim:

1. A unitary rail anchor consisting of a resilient plate constructed to extend under a rail between adjacent ties and having a jaw adapted to hook onto one flange of the rail base and a shoulder adapted to engage the opposite flange of the rail base, and lateral legs extending in opposite directions from one end of the plate and adapted to abut respectively against said ties. 70

2. A unitary rail anchor consisting of a plate constructed to extend under a rail between adjacent ties and having a jaw at one end adapted to grip one flange of the rail base and having a shoulder to engage the opposite flange of the rail base, and lateral legs extending in opposite directions from the shoulder-end of said plate and adapted to abut respectively against said ties. 80

3. A unitary rail anchor consisting of a plate constructed to extend under a rail between adjacent ties and having a jaw at one end adapted to grip one flange of the rail base and having a shoulder to engage the opposite flange of the rail base, and opposite legs extending laterally and downwardly from the shoulder-end of said plate and adapted to bear respectively against said ties. 90

4. A unitary rail anchor consisting of a plate constructed to extend under a rail between adjacent ties and having a jaw at one end adapted to grip one flange of the rail base and having a sectional shoulder to engage the opposite flange of the rail base, and lateral legs extending in opposite directions from the shoulder-sections and adapted to abut respectively against said ties. 100

5. A rail anchor comprising a plate constructed to extend under a rail base between adjacent ties and having a jaw at one end adapted to grip one flange of the rail base and having a shoulder to engage the opposite flange of the rail base, said plate having a longitudinal slit extending through said shoulder, lateral legs extending from the plate on opposite sides of said slit and adapted to abut respectively against said ties, and a key seated in the shoulder to overlie the associated flange. 110

6. A rail anchor comprising a plate constructed to extend under a rail base between adjacent ties and having a jaw at one end adapted to grip one flange of the rail base and having a shoulder to engage the opposite flange of the rail base, said plate having a longitudinal slit extending through said shoulder, lateral legs extending downwardly from the plate on opposite sides of said slit and adapted to abut respectively against said ties, and a key seated in the shoulder to overlie the associated flange. 120

7. A rail anchor comprising a plate constructed to extend under a rail base between adjacent ties and having a jaw at one end adapted to grip one flange of the rail base and having a shoulder to engage the opposite flange of the rail base, said plate having a longitudinal slit extending through said shoulder, lateral legs extending downwardly from the plate on opposite sides of said slit and adapted to abut respectively 10 against said ties, a transverse seat in the shoulder above its associated base-flange, and a key constructed to enter and interlock with said seat.
- 5 In testimony whereof I hereto affix my 15 signature.

WARREN M. OSBORN.
